Primary Examiner — Kevin K Rudzinski*Assistant Examiner* — Richard Kearney(74) *Attorney, Agent, or Firm* — Mitchell Law PLLC;
Matthew W. Mitchell(57) **CLAIM**

The ornamental design for a jewelry clasp chain, as shown and described.

DESCRIPTION

FIG. 1 is a front isometric view showing my new design;
FIG. 2 is a top plan view thereof;
FIG. 3 is a bottom plan view thereof;
FIG. 4 is a front side view thereof;
FIG. 5 is a rear side view thereof;
FIG. 6 is a left view thereof;
FIG. 7 is a right side view thereof;
FIG. 8 is an enlarged isometric view of the circled portion shown in FIG. 1; and,
FIG. 9 is an enlarged top plan view of the circled portion shown in FIG. 2.
The broken lines showing a necklace illustrate environmental structure that forms no part of the claimed design.

1 Claim, 9 Drawing Sheets(56)
